MECHANICAL MOVEMENT FOR CHENILLE,
EMBROIDERY, AND OTHER MACHINESKonrad Meier, Guttenberg, N. J., assignor to
Humbert Darista, New York, N. Y.

Application October 20, 1939, Serial No. 300,346

10 Claims.

(Cl. 74—76)

This invention relates to new and useful improvements in a mechanical movement for chenille, embroidery and other machines.

The invention has for an object the construction of a mechanical movement which is capable of oscillating a plurality of lines of gears. These gears may be utilized to work the bobbins or other parts of the machine, in mind.

Still further the invention proposes the provision of a plurality of rack bars simultaneously meshing with the gang of gears and a novel arrangement for reciprocating the rack bars to accomplish the oscillatory movement.

Still further the invention proposes to characterize the reciprocating mechanism by the provision of T-shaped members pivotally mounted at the center of their horizontal arms and having their vertical arms connected with the rack bars to reciprocate them as the T-shaped members are oscillated, and a novel means for oscillating the T-shaped members.

Still further the invention proposes to utilize vertical rods, arranged in line with the ends of the horizontal arms in a way so as to oscillate the T-shaped members when the rods are alternately moved upwards and downwards.

Still further the invention proposes a novel mechanism for moving said vertical rods upwards and downwards.

Another object of the invention resides in so constructing the mechanical movement that adjustments are possible to control the distance through which the rack bars are reciprocated.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a fragmentary side elevational view of a mechanical movement constructed in accordance with this invention.

Fig. 2 is an elevational view of Fig. 1.

Fig. 3 is a fragmentary horizontal sectional view taken on the line 3—3 of Fig. 2.

Fig. 4 is a perspective view of a top rack used in the device.

Fig. 5 is a perspective view of an auxiliary bracket used in conjunction with the bracket shown in Fig. 4.

Fig. 6 is a perspective view of the bottom bracket used in the device.

Fig. 7 is a perspective view of an auxiliary

bracket used in conjunction with the bracket shown in Fig. 6.

Fig. 8 is a perspective view of a certain disc used in the device.

Fig. 9 is a perspective view of one of the T-shaped members.

Fig. 10 is a perspective view of a portion of one of the means for connecting the vertical rods with the ends of the horizontal arms of the T-shaped members.

Fig. 11 is a perspective view of one of a plurality of abutment members used in conjunction with the vertical rods.

The mechanical movement in accordance with this invention includes an upper horizontal rack bar 12 and a lower horizontal rack bar 13 arranged to reciprocate and adapted to turn a top gang of gears 14 and a bottom gang of gears 15, respectively. These gears may comprise the bobbin or other gears of a chenille manufacturing machine, or an embroidery machine, or other machines of other types. In a chenille manufacturing machine it is customary to have as many as 124 gears in each of the upper and lower gangs of gears, for use in conjunction with the 124 needles of the machine. Each of the bobbin gears 14 and 15 has an opening 16 in its side through which the chenille material passes. Each gear is also provided with an opening 17 through which the needle passes. The details of the machine to which the invention is applied forms no part herein and therefore such disclosure will not be given. The fundamental purpose of this invention is to provide a novel mechanism adapted to oscillate a plurality of gangs of gears such as the gears 14 and 15, backwards and forwards, through predetermined amplitudes.

The mechanical movement includes a top bracket 18 which is mounted upon the frame 19, see Fig. 1, of the machine to which the mechanical movement is applied. This top bracket 18 has side arms 18^a upon which a pair of vertical straps 20 are fixedly mounted. A rack bar 12 engages through these vertical arms 20 so as to be limited to horizontal sliding only. A bottom bracket 22 is also mounted on the frame 19 and has a pair of side arms 22^a upon which a pair of vertical straps 23 are fixedly mounted. The bottom rack bar 13 slidably engages through these straps 23.

A T-shaped member 24 is pivotally mounted at the center of its horizontal arm on each of the brackets 18 and 22. A means is provided for the vertical arm of each of the T-shaped members for connecting with each of the adjacent rack bars, to reciprocate the rack bars as the T-shaped members are oscillated. This means includes a block 25 of non-circular form mounted on the side of the rack bar by a pintle 26. The non-circular block 25 engages into a slot 27 formed

in the vertical arm of the T-shaped member. As each T-shaped member 24 oscillates about its supporting pintle 28, its associated rack bar will reciprocate, in that the block 25 will be moved by the vertical arm of the T-shaped member. The block 25 is capable of sliding in the slot 27 to compensate for the arcuate path taken by the vertical arm of the T-shaped member in relation to the horizontal path taken by the rack bar.

A pair of vertical rods 30 and 31 are arranged in line with the ends of the horizontal arms of the T-shaped members 24 and are slidably mounted to be reciprocated upwards and downwards. More specifically the upper portions of the rods 30 and 31 pass through bearings 32 formed in an auxiliary bracket 32 which is mounted around the bottom portion of the top bracket 18 by several holding screws 33. Intermediate portions of the vertical rods 30 and 31 slidably pass through bearings 34' formed in another auxiliary bracket 34 which is mounted upon the upper portion of the bracket 22 by several fastening screws 35.

A means is provided for each of the vertical rods 30 and 31 for connecting them to the adjacent ends of the horizontal arms of the T-shaped members 24 to oscillate the T-shaped members when the vertical rods are reciprocated in opposite directions. This means includes a U-shaped block 36 for each end of each horizontal arm of each T-shaped member. Each U-shaped block 36 is mounted upon one or the other of the vertical rods 30 and 31 by several set screws 37 passing through the block and abutting the vertical rod. The arms of each U-shaped block 36 engage above and below a block 38 which is mounted on the end of the horizontal arm of the T-shaped member. The arrangement is such that when the vertical arms 30 and 31 move vertically upwards and downwards the T-shaped members will be oscillated with the blocks 38 pivoting and moving laterally between the arms of the U-shaped blocks 36.

A shaft 40 is rotatively supported through bearing portions 34^a formed on the auxiliary bracket 34. A disc 41 is fixedly mounted on the shaft 40 between the bearing portion 34^a, and at a location between the vertical rods 30 and 31. This disc has a lug portion 41^a through which set screws 42 engage for accomplishing the attachment of the disc on the shaft. Eccentric members 43 are mounted on opposite faces of the disc 41.

The disc 41 is formed with a pair of slots 44 formed on a diameter line thereof. Each of the slots 44 is surrounded by an elongated boss 45. These bosses 45 are arranged on opposite sides of the disc 41. The eccentric members 43 are adjustably mounted upon the bosses 44. This is accomplished by cap screws 46 passing through the slots 44 and threadedly engaging into the eccentric members 43. The cap screws 43 may be loosened and then the eccentric members radially adjusted upon the disc 41.

Each eccentric member 43 is cooperative with an abutment member 47, which is adjustably mounted on each of the vertical rods 30 and 31. Each abutment member 47 is fixedly held in adjusted positions by several cap screws 48 which threadedly engage through one of the sides thereof and abut the vertical rods. Each abutment member 47 is provided with a forwardly extending lug portion 47^a arranged in the path of mo-

tion of the eccentric members 43 when the disc 41 rotates.

A means is provided for rotating the disc 41. This means includes a sprocket wheel 50 mounted on the shaft 40 and engaged by a chain 51 engaging over a driver sprocket wheel 52. This driver sprocket wheel may be synchronized with a portion of the machine to which the mechanical movement is applied.

The top bracket 18 is provided with a lug 18^b having a slot 54 to assist in mounting the bracket on the frame 19. The frame 19 has a complementary lug 19^a for this purpose into which a holding element which passes through the slot may engage. The bottom bracket 22 is provided with an intermediate lug 22^b and a bottom lug 22^c. These lugs are formed with elongated slots 53 through which fastening elements may engage. The lugs 22^b and 22^c are cooperative with complementary lugs 19^b and 19^c of the frame 19. Fastening elements engage through slots 53 for assisting in securely holding the bracket in position on the frame 19.

The operation of the device is as follows:

The chain 51 will be driven continuously in one direction by the driver sprocket 52. The chain will rotate the sprocket wheel 50 continuously in one direction. This indirectly rotates the disc 41 causing first one of the eccentric members 43 to engage one of the projecting lug portions 47^a of one of the abutment members 47. This moves one of the vertical rods downwards. The downward motion of the vertical rod is communicated to oscillate the T-shaped members 24 in one direction. Motion of the T-shaped members is communicated to the other one of the vertical rods to move it upwards. Thus upon further rotation of the disc 41 the other abutment member 43 will engage the projecting lug portion 47^a of the other abutment member moving it downwards and so causing a return oscillation upon the T-shaped members. In this way as the disc 41 keeps turning the T-shaped members will oscillate forwards and backwards. The motion of the T-shaped members will be communicated to the racks 12 and 13, which in turn will oscillate the gangs of gears with which they mesh.

The amplitude of oscillation of gangs of gears will be controlled by varying the positions of the abutment members 47 upon the rods 30 and 31. These abutment members are moved upwards or downwards, as desired, to change the relationship with respect to the eccentric members 43. The relationship may be changed so that each eccentric member will move each of the abutment members 47 through a different distance. This controls the motion of the racks 12 and 13. The frictional resistance of the gang of gears are depended upon to hold the racks in various stationary positions, during that period when the eccentric members 43 do not contact with the lugs 47^a of the abutment members 47.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A mechanical movement for chenille, embroidery and the like machines, comprising an

upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, and means for rotating said shaft.

2. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped member when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, and means for rotating said shaft, each of said brackets supporting vertical straps through which said horizontal rack bars slidably engage to accomplish said slidable supporting of said rack bars.

3. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped member when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, means for rotating said shaft, and means by which the eccentric members may be radially adjusted upon said disc.

4. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said

vertical rods, eccentric members mounted on said disc, abutment members for the eccentric members and mounted on said vertical rods, and means for rotating said shaft, the means for connecting the vertical arms of the T-shaped members with the racks, includes a non-circular block pivotally mounted on each rack and engaging a slot formed in each vertical arm of the T-shaped members.

5. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, and means for rotating said shaft, the means for connecting the vertical rods with the ends of the horizontal arms of the T-shaped members includes U-shaped members mounted upon the vertical rod and having their arms engaging opposite sides of blocks mounted upon the ends of said horizontal arms.

6. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped member when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, means for rotating said shaft, and means by which the eccentric members may be radially adjusted upon said disc.

7. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said

- upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, and means for rotating said shaft, said abutment members being adjustably mounted on said vertical rods, each abutment member being releasably fixedly held in position by support screws threadedly engaging through the material thereof and abutting the material of the vertical rods.
9. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, means for rotating said shaft, and an auxiliary bracket mounted upon said bottom bracket and having bearing portions supporting said shaft.
10. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, means for rotating said shaft, and auxiliary brackets mounted upon said brackets and having bearings for supporting said vertical rods.
7. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, means for rotating said shaft, and an auxiliary bracket mounted upon said bottom bracket and having bearing portions supporting said shaft.
8. A mechanical movement for chenille, embroidery and the like machines, comprising an upper horizontal rack bar and the lower horizontal bar for reciprocating and turning a top gang of gears and a bottom gang of gears, a top bracket horizontally and slidably supporting said upper rack bar, a bottom bracket horizontally and slidably supporting said lower rack bar, a T-shaped member pivotally mounted at the center of its horizontal arm on each of said brackets, means for the vertical arm of each T-shaped member for connecting it with the adjacent rack bar to reciprocate the rack bar as the T-shaped member is oscillated, a pair of vertical rods in line with the ends of the horizontal arms of said T-shaped members and slidably mounted, means for the vertical rods for connecting them with the adjacent ends of the horizontal arms to oscillate the T-shaped members when reciprocated in opposite directions, a rotatively mounted shaft at right angles to said vertical rods, a disc mounted on said shaft and located between said vertical rods, eccentric members mounted on said disc, abutment members for the eccentric members and mounted on said vertical rods, means for rotating said shaft, and auxiliary brackets mounted upon said brackets and having bearings for supporting said vertical rods.
